TWISTING CAP

Filed Aug. 20, 1932

UNITED STATES PATENT OFFICE

1,928,253

TWISTING CAP

Richard Gollong, Johnson City, Tenn., assignor
to American Glanzstoff Corporation, New
York, N. Y., a corporation of Delaware

Application August 20, 1932. Serial No. 629,690

3 Claims. (Cl. 117—23)

My present invention relates to the provision of an improved cap adapted for use with a twisting machine.

In the handling of artificial and kindred threads and filaments great difficulty has heretofore been encountered in retaining the cap on the spindle and against the spool or bobbin mounted thereon. Since the spindle and spool must be rotated at a high rate of speed, the caps have a tendency to fly off the spindle causing both damage to the caps and also to the threads or filaments wound on the spools. The caps which have heretofore been used are complicated in construction and, in use have been unsatisfactory in operation.

Accordingly, it is an object of my present invention to provide an improved cap having associated therewith means to engage the spool which is efficient in operation.

Another object of my present invention is to provide an improved cap having associated therewith a ring having a plurality of means which will engage a spool mounted on a suitable spindle which will prevent the cap from flying off the spindle when the same is rotated at the high rate of speed necessary to impart the desired twist to the thread or filaments on the spool.

A further object of my present invention is to provide an improved cap for use on a twisting machine spindle and having associated therewith a ring carrying a plurality of locking or holding means which, when the spindle is rotated at a high rate of speed, are moved by the centrifugal action of the rotating spindle into engagement with a spool mounted on said spindle.

These and other objects of my present invention will become more apparent from a study of the following description and the drawing in which:

Fig. 1 is a sectional view of my improved cap and locking means;

Fig. 2 is a top plan view of the same; and

Fig. 3 is a view of the locking ring showing in detail the construction of the locking and holding members.

Referring now more particularly to the drawing, I have shown in detail a preferred embodiment of my present invention. The cap 10 is provided with a centrally located upstanding hub 11 in which the spindle 12 of a twisting machine (not shown) is adapted to fit. The cap is circular in shape and is provided with an outer circumferential wall 13. The edge of the wall is reversely bent as indicated at 14 providing a suit-

able seat 15 for the beaded edge of the spool 16. The wall 13 is provided at spaced intervals with a plurality of openings 17 for a purpose to be hereinafter described. These openings are preferably located at intervals of 90° around the cap.

The locking means, shown in detail in Fig. 3, comprises an annular ring 18 adapted to fit around the hub of the cap as is clearly indicated in Fig. 1. This ring may be made of soft rubber, rubber composition, or any other suitable material of resilient nature. The ring is provided at suitable intervals preferably at 90° intervals with resilient lugs or projections 19 adapted to fit snugly in and project through the openings 17 formed in the cap. To position the ring firmly on the cap there is provided a plurality of lugs or projections 20 which, when the ring is in place on the cap with the lugs 19 projecting through the openings formed therein, bear against the inner side of the wall 13.

In operation the ring is secured in place in the cap and the cap is then placed on the spindle, the beaded edge of the spool fitting in the seat formed in the cap. It will be noted that the lugs or projections 20 projecting through the openings provided therefor frictionally engage the inner wall of the spool. Upon rotation of the spindle the centrifugal force generated by such rotation forces the ring more firmly against the inner wall of the cap and consequently the lugs or projections are moved outwardly and are pressed more firmly against the inner surface of the spool. Thus with the increase in rotation of the spindle the more positively will the locking means function.

From the above description it will readily be appreciated that I have devised a cap having a simple and efficient locking means which will not loosen when rotated at a high rate of speed but, on the contrary, will be held more firmly against the spool.

While a preferred embodiment of the apparatus to be used in carrying out my invention has been described, it is to be understood that many changes may be made in the construction of the device without departing from the spirit of my invention or the scope of the appended claims.

What is claimed as new is:

1. A spool holder comprising a cap having an upstanding marginal rim provided with a plurality of openings formed therein and having a hub portion adapted to receive a spindle, an annular ring positioned on said cap provided with a plurality of projections, alternate projections bearing against said rim, the remaining pro-

2

jections projecting through said openings and adapted to engage a spool.

2. In a twisting machine, a spindle, a spool mounted thereon, a cap for holding said spool on said spindle comprising a body portion having an upstanding marginal rim provided with a plurality of spaced openings, a ring positioned on said body portion and provided with means projecting through said openings and locking said cap to said spool upon rotation of said spindle, said ring also being provided with a plurality of projections engaging said marginal rim between said openings.

3. A spool holder comprising a cap having an

15

upstanding marginal rim provided with a plurality of openings formed therein, said openings being substantially equidistant from one another, said cap having a hub portion adapted to accommodate a spindle, a flexible ring positioned on said cap, and provided with a plurality of projections, said projections being a multiple of the number of openings in said rim, each projection being an equal distance from every other projection, one of the projections extending through each of said openings in said rim, the remainder of said projections bearing against said rim.

RICHARD GOLLONG.
